UNITED STATES PATENT OFFICE.

JAMES BUCKNER SPEED, OF NEW YORK, N. Y., ASSIGNOR TO WESTERN ELECTRIC COMPANY, INCORPORATED, OF NEW YORK, N. Y., A CORPORATION OF NEW YORK.

TRANSMITTING DEVICE.

Application filed November 19, 1919. Serial No. 339,217.

To all whom it may concern:

Be it known that I, JAMES BUCKNER SPEED, a citizen of the United States of America, residing at New York, in the county of New York, State of New York, have invented certain new and useful Improvements in Transmitting Devices, of which the following is a full, clear, concise, and exact description.

10 This invention relates in general to transmitting devices and particularly to transmitters for signaling purposes.

An object of the invention is to provide a sound responsive device which shall be selectively responsive to vibrations of one or more particular frequencies and which shall be unresponsive to vibrations of other frequencies.

The invention comprises a pair of normally separated electrodes, one or both of which are to be supported upon a vibratory member individual thereto and each of the electrodes so supported constitutes with its supporting member a moving system having a chosen natural period, and operating when subjected to vibrations of its natural period to engage the electrodes.

The drawing illustrates one embodiment of the invention as applied to a transmitter of the variable resistance type in which the electrodes are normally out of contacting relationship, but wherein the electrodes are designed to engage with each other at the one or more selected frequencies of sound vibration.

This form of transmitter shown comprises a front plate 5 which carries the usual mouthpiece 6. A recess 7 at the rear of the front plate 5 provides a seat for a diaphragm 8, which is held in this recess by a clamping ring 9 secured to the front plate. A rubber ring 10 surrounding the periphery of the diaphragm 8 serves to insulate this diaphragm from the front plate and also enables the diaphragm to be held firmly in place between the front plate and the clamping ring 9.

The variable resistance element illustrated consists of a pair of electrodes 11 and 12, one being suitably mounted on the diaphragm 8 and the other being mounted on a diaphragm 13.

The particular transmitter illustrated by the drawing is designed to be operative only at two substantially different frequencies of

sound vibration. This is accomplished in the present instance by mounting the front electrode 11 on one vibrating element, such as the diaphragm 8, and the rear electrode 12 on another vibrating element, such as the diaphragm 13. The actual and relative size and mass of the diaphragms 8 and 13 together with that of the electrodes 11 and 12 and the annular member 14 will depend on the particular frequency or frequencies to which it is desired to have the transmitter selectively responsive. The diaphragm 13 is mounted on the larger front diaphragm 8 by means of the annular supporting member 14. The diaphragm 8 is of considerably larger diameter than the diaphragm 13 and hence has a slower period of vibration. In addition, the mass of the diaphragm 13 and its supporting member 14 appreciably lowers the frequency of the carrying diaphragm 8. Variation of the size, mass, or both, of any one or more of these elements is relied upon in the production of transmitters responsive to sounds of different particular frequencies.

This proportioning is such that the natural period of the diaphragm 8 with the electrode 11 thereon considered together is the same as the period of one of the sound vibrations to which the transmitter is to be responsive, and is also such that the natural period of the diaphragm 13 with the electrode 12 thereon considered together is the same as another of the sound vibrations to which the transmitter is to be responsive. If it is desired to have the transmitter responsive to substantially one frequency only, the proportioning of the diaphragms and their respective electrodes considered together will be such that the natural periods thereof will be substantially the same in each case; this period to be the same as the frequency of the particular sound to which it is desired to have the transmitter selectively responsive.

The electrodes 11 and 12 are preferably of silicon carbide, or carborundum, as disclosed in my copending patent application Serial Number 339,216, filed November 19, 1919, and as disclosed in such pending application the electrode 11 has preferably a plane contacting surface, and the electrode 12 a convex contacting surface having a radius of approximately eight meters. This feature is not however essential to the present in-

vention inasmuch as electrodes of any suitable construction and material can be used in the transmitting device forming the subject matter of the present application.

5 The electrodes 11 and 12 are normally out of contact and the construction of the transmitter is such that they engage only while the transmitter is subject to sound vibrations of the frequency or frequencies to which it 10 is selectively responsive. As shown, the electrodes 11 and 12 cooperate to control the making and breaking of a circuit including in addition thereto a battery 15 and the primary winding of a transformer 16; this circuit being normally open between the electrodes.

In operation, sound vibrations impinging on the diaphragm 8 set it in motion and some motion is also imparted thereby to the 20 diaphragm 13; which with its electrode 12 has a certain inertia effect, which, to a limited degree, influences its displacement. The movement of the two diaphragms 8 and 13 forces the electrodes 11 and 12 toward and 25 away from each other but under proper operating conditions the amplitude of movement of these electrodes is not sufficient to engage them except at the chosen frequencies. On sound vibrations of the same frequency as the natural period of the diaphragm 8 and the electrode 11 considered together striking this diaphragm however, an increased amplitude of movement is imparted thereto due to its greater responsiveness to sounds of its natural period. This 30 increased movement is sufficient to engage the electrodes 11 and 12 during such vibration and results in alternate completion and interruption of the circuit controlled thereby so long as and as often as sounds of substantially such particular frequency are impressed upon the diaphragm 8.

The construction of the transmitter is preferably such that the movement of the diaphragms 8 and 13 will not be interfered with by air confined therebetween; and such interference is prevented in the construction shown by providing a number of relatively large holes 17 in the member 14 to permit free ingress and egress of air to the space between these electrodes.

The same general action, as described for the diaphragm 8 and electrode 11 also takes place when sound vibrations of substantially the same frequency as the natural period of the diaphragm 13 with its electrode 12 considered together reaches the transmitter; the movement of the diaphragm 13 being increased under these conditions and thus effecting the engagement of the electrodes 11 and 12 and the alternate interruption of the circuit controlled thereby in the same manner as previously described.

When the natural periods of the two dia-

phragms 8 and 13 with their respective electrodes 11 and 12 are substantially different, sound vibrations of frequencies intermediate such natural periods, but substantially different therefrom, will not cause the engagement of the electrodes.

During the alternate completion and interruption of the primary circuit in response to sound vibrations of the frequency or frequencies to which the transmitter is selectively responsive, the current through the primary winding of the transformer 16 is correspondingly increased and decreased and thus induces similar current fluctuations in the secondary winding of the transformer. The latter current fluctuations can be readily detected by a suitable receiving or recording device operatively associated with the circuit including the secondary winding of the transformer 16. Inasmuch as no current change takes place in the transformer except in response to the engagement of the electrodes 11 and 12, the actuation of the receiving or recording device by current from the circuit including the secondary winding of the transformer, serves to indicate that the transmitter is receiving sound vibrations of a frequency to which it is selectively responsive. In event the transmitter selectively responds to sound vibrations of two substantially different frequencies, as is the case of the transmitter shown, the particular frequency being received by the transmitter may be detected, due to the fact that the sound vibrations having the higher frequency will result in the production of a tone of higher pitch in the receiving device, or of a record indicating a greater number of vibrations over a given record unit, than are obtained in response to sound vibrations of the lower frequency acting on the transmitter.

What is claimed is:

1. A sound responsive device of two substantially different particular frequencies comprising a pair of normally separated electrodes, a vibratory member supporting one of the electrodes, and a vibratory member supporting the other of the electrodes, each vibratory member and the respective electrode supported thereby forming a moving system having a chosen natural period, and the chosen natural period of one moving system being substantially different from the chosen natural period of the other moving system; one of said vibratory members being supported by the other whereby said electrodes are brought into contact when said moving systems are vibrated at either of the two chosen natural periods.

2. A sound responsive device comprising a pair of normally separated electrodes, a first diaphragm supporting one of the electrodes, a second diaphragm supported wholly from the first diaphragm and carry-

ing the other of the electrodes, and means connecting the first diaphragm to the second diaphragm, the two diaphragms and the respective electrodes forming a plurality of moving systems each having a chosen natural period; said electrodes being arranged to be brought into contact on subjection of the diaphragms to vibrations of the same period as the natural period of one of the moving systems.

3. A sound responsive device comprising an electrode, a diaphragm supporting said electrode, an annular member mounted on said diaphragm, a second diaphragm mounted on said annular member, an electrode mounted on said second diaphragm adjacent to but normally separated from said electrode, the two diaphragms and their respective electrodes forming moving systems, each having a chosen natural period; said electrodes adapted to be brought into contact on subjection of the diaphragms to vibrations of the same period as the natural period of one of the moving systems.

4. A sound responsive device of two substantially different particular frequencies comprising an electrode, a diaphragm supporting said electrode, said diaphragm and electrode comprising a moving system having a chosen natural period, an annular member mounted on said diaphragm, a second diaphragm mounted on said annular member, an electrode mounted on said diaphragm adjacent to but normally separated from said first electrode, said second diaphragm and electrode forming a moving system having a chosen natural period substantially different from that of the first moving system; said electrodes adapted to be brought into contact on subjection of the diaphragms to vibrations of the same period as the natural period of one of said moving systems.

In witness whereof, I hereunto subscribe my name this 17th day of November A. D., 1919.

JAMES BUCKNER SPEED.
